CLAIM

The ornamental design for a tumbler with sleeve, as shown and described.

DESCRIPTION

FIG. 1 is a perspective view of a tumbler with sleeve showing our new design;

FIG. 2 is a front view thereof;

FIG. 3 is a right side thereof;

FIG. 4 is a rear view thereof;

FIG. 5 is a left side view thereof;

FIG. 6 is a top view thereof;

FIG. 7 is a bottom view thereof;

FIG. 8 is an exploded view thereof shown in a reduced scale; and,

FIG. 9 is a cross-sectional view thereof taken along line 9-9 of FIG. 6.

The broken lines in the figures illustrate the portions of the tumbler with sleeve that form no part of the claimed design.

1 Claim, 8 Drawing Sheets
